ROLLER MASSAGE UNIT

John Waldeck, 2764 Faber Ave.,
Cincinnati, Ohio 45211

Filed Apr. 4, 1968, Ser. No. 11,308

Term of patent 14 years

Int. Cl. D24—99

U.S. CL. D83—1

FIGURE 1 is a perspective view of a roller massage unit showing my new design;

FIGURE 2 is a top plan view of the arm roller portion shown separately for clarity of illustration;

FIGURE 3 is a side elevation thereof;

FIGURE 4 is a top plan view of the foot roller portion shown separately for clarity of illustration;

FIGURE 5 is a side elevation thereof; and

FIGURE 6 is a perspective view of the neck roller portion shown separately for clarity of illustration.

I claim:

The ornamental design for roller massage unit, substantially as shown and described.
